REFINING HYDROCARBON MATERIALS
WITH SO₂ AND BF₃

Robert C. Arnold, Park Forest, Ill., and Arthur P. Lien, Highland, Ind., assignors to Standard Oil Company, Chicago, Ill., a corporation of Indiana

Application September 29, 1951, Serial No. 248,898

14 Claims. (Cl. 196—24)

1

This invention relates to a process for refining organic materials containing one or more undesired impurities, such as coloring matter, malodorous materials, and sulfur or sulfur compounds. More particularly, this invention is concerned with a process for refining, and especially for desulfurizing, hydrocarbon materials such as sulfur-containing hydrocarbon oils, e. g. petroleum oil fractions.

One object of the present invention is to provide a process for refining and desulfurizing hydrocarbon materials containing sulfur and/or organic sulfur compounds. Another object of our invention is to provide a process for substantially deodorizing "sour" or mercaptan-containing hydrocarbon materials. An additional object is to provide a process for decolorizing hydrocarbon materials, particularly hydrocarbon oils. Still another object of our invention is to provide novel mixtures of chemical compounds characterized by a remarkably specific and selective interaction with organic sulfur compounds. These and other objects of our invention will become apparent from the ensuing description thereof.

The problems of refining hydrocarbon materials, particularly of decolorizing, deodorizing and desulfurizing said materials, have assumed increasing importance in the petroleum, coal derivatives and synthetic fuel industries. Attempts have heretofore been made to utilize the refining properties of BF₃ alone and in combination with various complex compounds of BF₃ and oxygenated organic compounds, such as ethers, esters and carboxylic acids, as set forth in U. S. Patent 2,495,851 of Arthur P. Lien and Bernard L. Evering, issued January 31, 1950. Although free BF₃ in combination with complexes of BF₃ and various oxygenated organic compounds has substantial utility for desulfurizing hydrocarbon oils, both the extent of desulfurization and selectivity of these combination solvents heretofore known has left something to be desired.

Briefly, we have made the surprising discovery that mixtures of BF₃ and liquid sulfur dioxide exhibit a remarkable refining capacity for hydrocarbon materials containing sulfur or organic sulfur compounds and/or coloring impurities and/or odoriferous materials, particularly mercaptans. Especially remarkable is the ability of mixtures of BF₃ and liquid sulfur dioxide to combine selectively with organic sulfur compounds contained in hydrocarbon oils, thereby producing solutions of said sulfur compounds in

2

the BF₃-liquid sulfur dioxide mixtures, which solutions are substantially insoluble in the resultant refined hydrocarbon oils at the refining temperatures which are employed in our process. 5 We have discovered that refining agents comprising essentially BF₃ and liquid sulfur dioxide are characterized by an unexpectedly high desulfurization capacity for hydrocarbon oils as compared with either reagent or the expected 10 sum of their individual desulfurization capacities; moreover, that the combined refining agents exert this unexpectedly increased desulfurization capacity without exhibiting a substantially greater dearomatization capacity than 15 liquid sulfur dioxide alone. As a result, the combined BF₃-liquid sulfur dioxide treating agent of the present invention leads to extensive desulfurization of sulfur-containing hydrocarbon materials at surprisingly high raffinate 20 yields.

In one particularly desirable aspect, our invention comprises contacting a hydrocarbon oil which is to be refined with a mixture of BF₃ and liquid sulfur dioxide, said mixture being present 25 in an amount sufficient to form a distinct liquid phase upon settling, and thereafter effecting stratification of the contacting mixture into a liquid layer comprising predominantly refined hydrocarbon oil, or raffinate, and a second, 30 immiscible layer comprising predominantly a solution or chemical combination of BF₃, liquid sulfur dioxide and impurities derived from the hydrocarbon oil charging stock, or extract.

The proportion of liquid sulfur dioxide, based 35 on the hydrocarbon material being refined, can be varied between about 15 and about 200 volume percent, more or less, depending upon the specific hydrocarbon material being treated and the treating conditions, especially the temperature. 40 The relative miscibility of liquid sulfur dioxide and hydrocarbon charging stocks varies with temperature, greater mutual miscibilities in general being encountered at higher temperatures and lower miscibilities at lower temperatures. In general we employ at least a sufficient amount of sulfur dioxide to exceed its solubility in the hydrocarbon material being treated at the treating temperature, thereby forming two distinct liquid phases, viz. a predominantly hydrocarbon liquid phase containing a relatively small proportion of dissolved sulfur dioxide and a predominantly sulfur dioxide liquid phase or extract layer. Ordinarily, liquid sulfur dioxide is employed in our process in 45 amounts between about 25 percent and about 50 amounts between about 25 percent and about 55 amounts between about 25 percent and about

100 per cent by volume, based on the volume of hydrocarbon charging stock.

The amount of BF_3 employed in our process will usually fall within the range of about 0.5 to about 5 mols of BF_3 per gram atom of sulfur contained in the hydrocarbon charging stock. As will be shown hereinafter, proportions of BF_3 to sulfur within the above range, when employed with liquid sulfur dioxide, are sufficient not only to effect substantial desulfurization of sulfur-containing hydrocarbon materials but also to effect additional refining, particularly decolorization. For purposes of desulfurization we have discovered the unexpected fact that optimum desulfurization can be effected by the employment of between about 1 and about 3 mols of BF_3 per gram atom of sulfur contained in the hydrocarbon charging stock, employing in addition a sufficient proportion of liquid sulfur dioxide to form a liquid phase distinct from the raffinate hydrocarbon material.

The present refining process may be conducted at temperatures of 10°C . or less, e. g., within the range of about 0°C . to about -85°C . Usually we employ temperatures between about -10°C . and about -50°C . In any given instance, bearing in mind a specific object of the refining process, it is readily possible to determine both the absolute and economically optimum temperatures by means of relatively few tests and standard engineering calculations.

The present refining process is conducted under pressure sufficient at least to maintain a substantial proportion of the sulfur dioxide in the liquid phase and likewise sufficient at least to maintain a substantial proportion of the BF_3 in the liquid phase in the presence of sulfur compounds. We have discovered that in the presence of liquid sulfur dioxide, BF_3 forms extremely stable addition compounds with sulfur compounds such as are frequently encountered in petroleum oils and, as a result, a substantial proportion of BF_3 which is originally introduced into the refining zone as a gas is rapidly absorbed. The partial pressure of BF_3 in equilibrium with said BF_3 -sulfur compound addition compounds is very low at temperatures of 0°C . or less. In general, the present process can be operated at pressures which are commonly encountered in commercial process equipment, for example between about 1 and about 300 p. s. i. g., although usually pressures between about 1 and about 15 p. s. i. g. are sufficient for the present purposes.

The time period required in the present refining process will be dependent, naturally, upon the intimacy of contacting with the refining agent of the hydrocarbon material being treated and upon the operating temperature. Ordinarily, the time period is selected between about $\frac{1}{2}$ and about 30 minutes. The operating temperature will, to some extent, affect the intimacy of contacting by determining the liquid viscosities in the refining system and, probably to a more important extent, by determining the rate of interaction of sulfur compounds and other impurities in the feed stock with the refining agent. Although the present process has been referred to as a refining or extraction process, there is reason to believe that the actual mechanism of refining in the present process is a chemical or quasi-chemical union of organic sulfur compounds, colored impurities and the like with the chemically reactive BF_3 -liquid sulfur dioxide refining agent. Inter- and intra-molecular conversions of sulfur compounds, especially of mercaptans,

also occur as shown by doctor-sweet raffinates and extracts. Doctor-sweet products may even be obtained without diphasic separation.

Various diluents, countersolvents or co-solvents can be employed in the present process in addition to the SO_2 - BF_3 refining agent. Especially in the case of viscous or relatively high pour point hydrocarbon charging stocks it may be desirable to dilute said charging stocks with diluents or countersolvents such as liquefied propane, butanes, pentanes, hexanes, saturated naphthas or the like. The use of various cosolvents, particularly benzol with liquid sulfur dioxide, is well-known and these co-solvents may find application in the process of the present invention.

The present refining process is applicable to various liquid or liquefied hydrocarbon materials. Thus, it is applicable to various petroleum fractions for the purposes of removing sulfur, gums or other resinous materials, colored impurities and odiferous compounds, particularly mercaptans. Suitable petroleum feed stocks may comprise light naphtha fractions, gasolines, heavy naphthas, kerosenes, transformer oils, heater oils, furnace oils, diesel fuels, gas oils, lube oils and crude oils. The present refining process can be applied for the purpose of desulfurizing various petroleum stocks which are to be subsequently treated in refining or conversion operations in which sulfur or sulfur compounds are undesirable, for example, catalytic cracking operations, catalytic reforming operations, catalytic hydroforming operations, catalytic hydrogenation in the presence of sulfur-sensitive catalysts and the like.

In addition, the BF_3 -liquid sulfur dioxide refining agents of the present invention may be applied to the desulfurization and decolorization of aromatic hydrocarbon fractions, for example crude benzols, toluls, xylols, naphthalene fractions or the like.

The present process may also be applied to the refining of various coal tar fractions and coal tar distillates. In the refining of shale oil fractions the present refining agents serve not only to remove organic sulfur compounds from the feed stock, but also to remove oxygen compounds and nitrogen compounds. It should be understood that the above specific examples of charging stocks which may be refined in accordance with the present invention are illustrative only and are not intended to limit the field of applicability of the process of the present invention.

We have found that it is possible to heat the total extract phase from our process until substantially all the SO_2 has been vaporized off without substantially decomposing the BF_3 -sulfur compound adduct, if the temperature of the extract phase does not exceed about 50°C . The free BF_3 , i. e. the BF_3 existing in simple solution in the extract phase, passes off along with the gaseous SO_2 . We have found that partial removal of the SO_2 will result in the separation of a second raffinate layer and the yield of the second raffinate reaches a maximum when substantially all the SO_2 and free BF_3 have been removed. When substantially all the SO_2 and free BF_3 have been removed from the first extract phase, the second raffinate consists essentially of all the aromatic hydrocarbons extracted from the feed stock and some sulfur compounds, as evidenced by the sulfur content thereof; and the second extract phase consists of an adduct of BF_3 and sulfur compounds and some SO_2 con-

tained therein. The amount of SO_2 present in the second extract phase may vary from about 1 to about 15 volume percent depending upon the temperature at which the first extract phase was heated in order to remove SO_2 and free BF_3 . We have found that the sulfur content of the aromatic hydrocarbon-containing second raffinate obtained by this SO_2 removal technique is less than the sulfur content of the total extract materials; and may be in some cases as low as 0.1 wt. percent.

When the extract phase is treated so as to remove substantially all the SO_2 and free BF_3 , the second extract material appears to consist essentially of organo sulfur compounds. Treatment of a West Texas heater oil containing 0.6 wt. per cent sulfur with 2 mols of BF_3 per mol of sulfur dissolved in 25 volume percent of liquid SO_2 , separation of the resultant extract phase and removal of the SO_2 and free BF_3 from the extract phase at about 25° C. gave a second extract material with a sulfur content of 12.1%. The second raffinate consisted of aromatic hydrocarbons and enough organo sulfur compounds to give a sulfur content of 4%.

The present process can be carried out in batch, continuous or semi-continuous operating cycles, and in one or more stages, employing contacting and separation equipment such as has heretofore been employed in the selective solvent refining of petroleum lubricating oil stocks or in effecting the alkylation of isoparaffinic hydrocarbons with olefins in the presence of liquid acid catalysts. It should be understood that the specific equipment employed forms no part of the present invention and that any equipment adaptable for the purposes of contacting the BF_3 -liquid sulfur dioxide refining agent with the hydrocarbon charging stock and thereafter separating spent refining agent from the refined charging stock can be employed for the purposes of the invention.

In order more fully to describe one specific embodiment of our invention, reference is made to Figure 1. The feed stock, for example a sulfur-bearing hydrocarbon material such as a West Texas virgin heater oil derived from distillation of a West Texas crude oil, is passed through valved line 10 into a drying zone 11 wherein it is substantially dehydrated. Drying zone 11 may comprise conventional equipment and drying reagents and may, for example, take the form of a vessel packed with calcium chloride, excelsior, fiber glass, magnesium silicate drying agents (Florisil), alumina gel or the like. Drying of the charging stock can also be effected by distillation, for example vacuum distillation. It should be understood that the specific drying treatment forms no part of the present invention and that any drying treatment may be used which substantially eliminates water from the charging stock. The presence of water in the charging stock and in the treating system is extremely undesirable since water combines with BF_3 to form hydrates, which complicates the recovery of BF_3 , and since the corrosive tendencies of the present BF_3 -sulfur dioxide refining agent tend to increase with increasing water concentration in the refining system.

The dried charging stock is passed through line 12 into deaeration equipment 13 wherein air dissolved in or entrained in the charging stock is substantially removed. The specific deaeration process and equipment form no part of the present invention. Vacuum deaeration equipment such as is ordinarily employed in commercial

processes of liquid sulfur dioxide refining of hydrocarbon oils can be employed. The deaerated charging stock is passed through line 14 into heat exchanger 15 wherein the temperature of the stock is lowered to the desired treating temperature.

If desired, the viscosity of the hydrocarbon charging stock can be reduced by dilution with a saturated hydrocarbon such as n-pentane, isopentane, n-octane, petroleum ether, methylcyclopentane, cyclohexane or the like which may be introduced into line 14 through valved line 16.

The hydrocarbon charging stock thus pretreated is introduced into the lower portion of refining or extraction tower 17. The extraction tower may be packed with suitable corrosion-resistant packing materials to increase the efficiency of contacting of the charging stock and refining agents. For example, the extraction tower can be packed with structural carbon in the form of Berl saddles, glass or porcelain spheres, Monel metal fragments, mild carbon steel jack chain or the like, or may be provided with mechanically- or magnetically-actuated agitators.

25 In tower 17 the hydrocarbon charging stock is contacted with liquid sulfur dioxide and BF_3 . If desired the combined reagents may be introduced into the upper portion of tower 17 through valved line 18 leading from storage drum 19. Alternatively, liquid sulfur dioxide alone may be introduced through line 18 and BF_3 may be introduced into the extraction zone through valved line 20 and manifold 21.

20 Contacting in extraction tower 17 may, for example, be effected at temperatures between about -10 and about -40° C. at pressures between about 0 and about 100 p. s. i. g. The amount of liquid sulfur dioxide introduced into tower 17 may, for example, be between about 25 and about 100 percent by volume, based on the volume of hydrocarbon charging stock and the amount of BF_3 may, for example, be between about 1 and about 3 mols per gram atom of sulfur contained in the hydrocarbon charging stock. Tower 17 may be operated raffinate-rich or extract-rich but we prefer the latter mode of operation. Meniscus 22 is shown in Figure 1 as the separation boundary between a lower liquid extract phase and a supernatant liquid raffinate phase comprising predominantly refined hydrocarbon stock. The contacting period in tower 17 can be varied between about 1/2 and about 30 minutes and may, for example, be about 5 minutes.

25 Raffinate is withdrawn from the upper end of tower 17 through line 23 into stripping tower 24 communicating at its lowest end with a reboiler 25. Tower 24 may be unpacked or may optionally contain bubble trays, packing materials or other fractionating devices. Raffinate is controllably withdrawn from the lower end of tower 24 through reboiler 25 and recycled to tower 24 to maintain temperatures therein within the desired range. Relatively small amounts of liquid SO_2 and BF_3 which have been occluded in the raffinate are vaporized in tower 24, usually at temperatures between about 30° C. and about 150° C. and withdrawn through line 26 for reuse. Stripped raffinate is withdrawn through valved line 27 for removal from the process or for such further treatment as may be desired, for example treatment with concentrated sulfuric acid or with selective solvents, redistillation to separate diluent which was introduced through valved line 16, alkali treatment, clay treatment, water washing or other refining treatment.

Extract is withdrawn from the lower portion of extraction tower 17 through valved line 28 for treatment to separate extract materials and the components of the refining reagent, respectively. In one mode of operation the extract layer is passed from line 28 into stripping tower 29, which may be unpacked or which may be provided with packing or fractionating materials such as bubble cap plates. Tower 29 is provided with a reboiler 30 through which liquid materials from the lower end of the tower are controllably circulated to maintain a desired temperature within the tower. The extract layer may be subjected to a sufficiently high temperature in tower 29 to vaporize substantially its entire content of sulfur dioxide and BF_3 . Such temperatures fall within the range of about 50° C. to about 250° C. Sufficient pressure must be maintained in tower 29 to prevent vaporization of the lower boiling portions of the extract. The sulfur dioxide and BF_3 pass overhead from tower 29 through line 31 thence through valved line 32, through purification equipment schematically illustrated by 33, thence through line 34, compressor 35 and condenser 36 into pressure storage vessel 19. When the gas stream passing through valved line 32 contains little or no hydrogen sulfide, it may be passed around purification equipment 33 through valved by-pass line 37. Stripped extract materials are withdrawn from the lower end of tower 29 through lines 38 and 39.

In another mode of operation, separation of the extract layer is effected in two stages. In the two-stage method of separating the extract layer, said layer is subjected in the first stage to relatively low temperature to effect vaporization of free sulfur dioxide and BF_3 , which can be circulated after compression and cooling to extraction zone 11 without requiring purification; the liquid residue of the first stage extract layer treatment is then subjected to a higher temperature to effect decomposition of BF_3 adducts with sulfur compounds and aromatic hydrocarbons, containing more or less sulfur dioxide. The high temperature extract treating stage results in some decomposition of sulfur compounds to form hydrogen sulfide and, as a consequence it is desirable separately to treat the gas stream derived from the second stage extract treatment to remove hydrogen sulfide therefrom prior to liquefaction and recirculation of said stream for reuse in extraction tower 17. The boiling points of sulfur dioxide, hydrogen sulfide and boron trifluoride lie sufficiently far apart to permit their ready separation by fractional liquefaction methods.

In the two-stage method of extract layer treatment, the first stage of treatment can be effected in tower 29, wherein it is desirable to maintain temperatures between about 20° C. and about 50° C. and pressures between about 1 and about 100 p. s. i. g. in order to prevent vaporization of the lower boiling portions of the extract. The partially stripped extract layer is then withdrawn from the lower end of tower 29 through line 38, thence through valved line 40 into tower 41 communicating with reboiler 42. Tower 41 is suitably maintained at a temperature between about 80° C. and about 250° C. and a pressure between about 1 and about 100 p. s. i. g. The gases evolved in tower 41 usually contain, in addition to BF_3 and sulfur dioxide, more or less hydrogen sulfide which is produced by partial thermal decomposition of sulfur compounds in tower 41. Gases are taken overhead from tower 41 through valved line

5 43 and can be recycled, in part, through line 45 into heat exchanger 46 and dehydrator 47, and, in part, through line 49 to extraction tower 17. Stripped extract materials are withdrawn from

10 the lower end of tower 41 through valved line 44. It is desirable from time to time to withdraw at least a portion of the stream passing through lines 31 and 43 through valved line 45 and heat exchanger 46 into a dehydrating tower 47 provided with reboiler 48 and its accompanying circuit. Suitable conditions are maintained in tower 47 to withdraw SO_2 and BF_3 as gases overhead through line 49 for recycle to extraction zone 17. A liquid bottoms fraction comprising water, sulfur dioxide and BF_3 hydrates is withdrawn from the lower portion of tower 47 through reboiler 48, whence an aliquot portion is withdrawn from time to time through valved line 50 for discharge from the system.

20 Stripped extract materials from lines 39 and 44 can be recirculated in part, optionally after dilution with a diluent such as a paraffinic naphtha, to the lower portion of extraction tower 17 to serve as a backwash. The employment of a back-washing operation increases the selectivity of the extraction operation in tower 17, particularly increasing the selectivity of the extraction operation for sulfur compounds as compared with aromatic hydrocarbons. The extent of backwash may vary from between about 5 to about 25 percent by volume of the hydrocarbon charge entering the lower portion of tower 17.

25 35 At least a portion of the extract materials passing through lines 39 and 44 can be subjected to various desired refining after-treatments. For example, a portion of the extract materials can be subjected to catalytic hydrofining treatment, employing a conventional catalyst, e. g., cobalt molybdate, and conventional operating conditions. These extract materials are a surprisingly good feed to a catalytic cracking operation; a high yield of very high octane gasoline is obtained, which gasoline has the remarkably low sulfur content of less than 0.1 wt. percent.

30 40 45 When a maximum yield of low sulfur raffinate oil is desired without regard to the presence of aromatic hydrocarbons therein, our process can be carried out in the following manner. The extract phase passes from extraction tower 17 through line 28 into stripper 29. In stripper 29 the extract phase is maintained at a temperature between about 20° and 50° C. under a pressure sufficient to maintain the lower boiling portion of the extract materials in the liquid state. We prefer to heat the extract phase in stripper 29 at about 50° C. until substantially all the SO_2 and free BF_3 have been taken overhead through line 31. The SO_2 and BF_3 pass overhead from tower 29 through line 31, through valved line 32 through purification equipment 33, through line 34, compressor 35 and condenser 36 into storage vessel 19.

40 50 55 60 65 The extract phase denuded of SO_2 and BF_3 passes out of stripper 29 through line 38 and line 64 into settler 62. In settler 62 the denuded extract phase separates into a second raffinate phase and a second extract phase. The second extract phase passes out of settler 62 through line 64 and line 40 into stripper 41.

60 65 70 75 80 The second extract phase which consists chiefly of organo sulfur compounds, BF_3 and some SO_2 is decomposed in stripper 41 by being heated to a temperature between about 75 and 250° C. under a pressure sufficient to keep the lower boiling portions of said second extract in the liquid state.

The products of the decomposition of the second extract phase pass overhead through valve line 43 or line 45 for treatment as previously described. The bottoms from tower 41 pass out through line 44 to storage not shown. The second extract material consists essentially of organo sulfur compounds.

The second raffinate phase passes out of settler 62 through line 66 and may be recycled back to extraction tower 17 by way of valved line 67. The second raffinate phase consists substantially of aromatic hydrocarbons and some organo sulfur compounds. When this material is introduced into the initial extraction tower either at a low point in the tower or along with the feed stock, the sulfur content thereof is extracted and passes out of the tower in the extract phase; a considerable portion of the aromatic hydrocarbons from line 67 are rejected by the liquid SO_2 - BF_3 solvent and appear in the raffinate and thereby increase the yield of said raffinate without any appreciable increase in sulfur content thereof.

If it is not desirable to recycle the second raffinate phase to the extraction tower, these materials pass through line 66 and 69 into stripper 71, which stripper is provided with a reboiler 72. In stripper 71 the BF_3 and SO_2 dissolved in the second raffinate are removed and pass overhead through line 73 to zone 33 for purification or through line 74 to line 45 for further purification. From the bottom of stripper 71 through line 76 the second raffinate materials pass to storage not shown. Dependent upon the feed stock and the conditions of operation of the extraction tower 17, this material consists of aromatic hydrocarbons and some organo sulfur compounds. The sulfur content of the bottoms from stripper 71 may vary from 0.1 wt. per cent to some amount less than the sulfur content of the total extract material from the initial extraction operation.

Numerous pumps, valves, heat exchangers and other engineering details have been omitted from Figure 1 in the interests of simplifying the description of the invention. Common engineering process expedients, particularly those which have heretofore been employed in processes of refining hydrocarbon oils with liquid sulfur dioxide will, no doubt, suggest themselves to those skilled in the art and it should be understood that such engineering expedients are within the purview of the present invention.

The following specific examples are supplied in the interests of illustrating but not unduly limiting the present invention. The table, below, presents data obtained in runs which are illustrative of the present invention. The charging stock was a West Texas virgin heater oil having the following inspections:

ASTM distillation		
Per cent S-0.73	IBP=332° F.	
n_{D}^{20} -1.4585	10% =390° F.	
API gravity=40.2		
(sp. gr. (60/60° F.)=0.8241)	50% =446° F.	
Color Saybolt=+13	90% =502° F.	
Mercaptan number=57.4	max.=548° F.	

The extraction procedure consisted of adding the indicated amount of liquid sulfur dioxide to 500 cc. of oil contained in a reactor provided with a cooling jacket and mechanical agitator. The temperature of the reactor contents was maintained at -20° C. except in Runs 14 and 15 in which temperatures of -35° C. and 0° C., respectively, were employed. The indicated amount

of BF_3 was metered into the reactor and the reactor was closed. At this point a pressure of from 10 to 100 p. s. i. g., due largely to BF_3 , prevailed in the reactor, but when agitation was started, the pressure fell rapidly to about 0 p. s. i. g. Agitation was continued for 5 minutes, followed by a 30 minute settling period to furnish ample time for the extract and raffinate phases to separate. The extract phase was drawn off at the bottom of the reactor and the raffinate phase was washed with water and then with 10% caustic. Finally the raffinate was again washed with water and dried.

The following factors have been developed to indicate the selectivity of the refining process for sulfur compounds and aromatic hydrocarbons, respectively:

Sulfur selectivity factor=

$$20 \frac{[(\text{Percent S in feed}) - (\text{Percent S in raffinate})] \times 10^4}{(\text{Percent S in feed})(100 - \text{V. percent raffinate})}$$

which is equivalent to

$$25 \frac{(\text{Percent desulfurization}) \times 10^2}{(100 - \text{V. percent raffinate})}$$

Aromatic selectivity factor=

$$30 \frac{[(n_D^{20} \text{ feed}) - (n_D^{20} \text{ raffinate})] \times 10^4}{[(n_D^{20} \text{ feed}) - (n_D^{20} \text{ aromatic-free feed})] [100 - \text{V. percent raffinate}]}$$

which is the substantial equivalent of

$$35 \frac{\text{Percent dearomatization}}{(100 - \text{V. percent raffinate})} \times 10^2$$

It was found that complete dearomatization of the feed stock with silica gel resulted in a refractive index of 1.4391 as compared with the initial refractive index of 1.4585.

The runs set forth in the table were obtained by the treatment of the heater oil with 25, 50 and 100 volume percent, respectively, of liquid sulfur dioxide, with and without the addition of BF_3 in the amounts indicated; the resultant desulfurization, dearomatization and raffinate yield values were determined. The percentage of desulfurization as a function of BF_3 and sulfur dioxide concentration is presented in Figure 2, except for Runs 14 and 15. It will readily be apparent from the table and Figure 2 that the addition of BF_3 to liquid SO_2 greatly increases the extent of desulfurization which is obtainable. The addition of BF_3 to liquid sulfur dioxide results in a very sharp increase in desulfurization of the charging stock up to the point at which about 2 mols of BF_3 per gram atom of sulfur contained in the heater oil charging stock have been added and thereafter the extent of desulfurization increases very little. In the case of this particular heater oil (specific gravity, 0.8241; sulfur content, 0.73 weight percent) 2 mols of BF_3 per gram atom of sulfur corresponds to about 9 pounds of BF_3 per 42-gallon barrel of heater oil. It will further be noted that the large and unexpected increase in desulfurization effected by the addition of BF_3 to liquid sulfur dioxide was obtained without substantial decrease in the yield of raffinate obtained by sulfur dioxide treatment alone. Thus, it will be apparent from the runs set forth in the table that with decreased raffinate yields in the range of only 1 to 3 percent, very large and unexpected increases of desulfurization were readily obtained, as will be noted, for example, by com-

11

parison of Runs 1 and 2, Runs 4 and 6, or Runs 10 and 12. It will further be noted that the percentage of dearomatization is essentially determined by the liquid sulfur dioxide concentration in the treating zone, being but little affected by the addition of even large molar excesses of boron fluoride as will be apparent, for example, by the

12

vapor pressure of BF_3 , indicating complex formation. Surprisingly, liquid sulfur dioxide, which is apparently structurally similar to the dimethylsulfolane, does not form a complex with BF_3 . The extent of desulfurization obtained in this experiment is about what would be expected from 3,4-dimethylsulfolane alone.

TABLE
Extraction of West Texas virgin heater oil with SO_2BF_3

¹ Temp., -35°C .

² Temp., 0°C .

comparison of Runs 4 and 9. It appears from the data in the table that the extent of sulfur extraction is much greater than could be expected from a knowledge of the individual desulfurization capacities of sulfur dioxide and BF_3 . A comparison of Run 14 with Runs 6 and 7 which are comparable but were effected at -20°C . as compared with the -35°C . temperature of Run 14, shows that somewhat increased desulfurization at high raffinate yield was obtained by using the lowered temperature. On the other hand, increasing the temperature to 0°C . in Run 15 resulted in a somewhat reduced extent of desulfurization as compared with operations at -20°C . as in Runs 6 and 7.

Although not indicated in the table, the color of sulfur dioxide- BF_3 raffinates is generally very good, ranging from +25 to +30 Saybolt (from +13 of feed). The only runs which failed to produce a good colored raffinate were those made at very high BF_3 treats, 6 to 8 mols BF_3 per gram atom of sulfur, and the run made at 0°C . (Run 15). Also not shown in the table is the effect of sulfur dioxide- BF_3 on mercaptan extraction. It was observed that Doctor sweet raffinates were obtained when the amount of BF_3 was equivalent to at least 2 mols per mol of sulfur. Lesser amounts of BF_3 gave slightly sour products, as determined by the standard Doctor test.

When the West Texas virgin heater oil was treated at -20°C . with BF_3 alone in the proportion of 2.7 mols per gram atom of sulfur contained in the oil, a sludge was produced, which was filtered from the refined oil. Analysis showed that only 19 percent desulfurization was attained. Repetition of the BF_3 treatment in the presence of 1 volume of hexane per volume of oil, showed that no phase separation could be obtained and no sludge formed; analysis of the oil thus treated failed to reveal any desulfurization whatever.

When the West Texas virgin heater oil was treated at -20°C . with 3,4-dimethylsulfolane and 2 mols BF_3 per gram atom of sulfur in the feed, only 21% desulfurization and a raffinate yield of 91 volume percent of feed were observed. The dimethylsulfolane markedly reduces the

RUN 16

The charging stock was a light catalytically cracked cycle oil or gas oil containing 1.45 weight percent sulfur and having a refractive index (n_{D}^{20}) of 1.5003. Extraction of this oil with 50 percent by volume of sulfur dioxide at -20°C . yielded 65 percent by volume of a raffinate containing 0.59 weight percent sulfur and having a refractive index of 1.4695. Extraction of the charging stock with 50 percent by volume of liquid sulfur dioxide and 1.9 mols BF_3 per gram atom of sulfur likewise yielded 65 percent of raffinate but the sulfur content thereof was reduced to 0.45 weight percent and the refractive index was increased to 1.4705. Thus, the inclusion of BF_3 in the refining agent increased the desulfurization of the charging stock from 59 percent to 69 percent without loss of raffinate yield and resulted in a more highly aromatic raffinate than the process employing liquid sulfur dioxide alone as the refining agent.

RUN 17

The charging stock was a naphtha obtained by distilling petroleum oils to coke, containing 0.66 weight percent of sulfur. Extraction of this stock with 50 percent by volume of liquid sulfur dioxide yielded 85 percent by volume of raffinate containing 0.413 weight percent of sulfur. Extraction of the charging stock with 50 percent by volume of liquid sulfur dioxide and 2.5 mols BF_3 per gram atom of sulfur yielded the same proportion of raffinate having the reduced sulfur content of 0.344 weight percent. Thus, the inclusion of BF_3 in the refining agent increased desulfurization of the charging stock from 37 to 48 percent without reduction in the proportion of raffinate.

While certain specific applications of the process of the present invention have been described above, it will be appreciated that numerous other applications of the present refining process can be made. As an example, the present process may be applied to raffinates from conventional liquid sulfur dioxide extraction processes which are known to contain residual sulfur compounds.

Moreover, the present process can be applied to

extracts of conventional liquid sulfur dioxide refining processes, preferably in the following manner. The liquid sulfur dioxide extract phase is partially stripped of sulfur dioxide. Although sufficient sulfur dioxide may be retained to maintain a homogeneous liquid phase at temperatures between about -25° C. and about -40° C., it is preferred to regulate sulfur dioxide removal to the point where two liquid phases just begin to appear at the temperatures indicated. The liquid bottoms from this stripping operation are then contacted with BF_3 in amounts between about 0.5 and about 4, preferably about 1.5 to about 2.5 mols, per gram atom of sulfur present in the extract material, whereupon a substantial proportion of the aromatic hydrocarbons in said extract material is thrown out of solution and may be separated as a supernatant phase. If desired, during the BF_3 contacting operation, a non-aromatic hydrocarbon stream boiling outside the range of the organic material of the liquid sulfur dioxide extract phase can be introduced as a countersolvent in order to increase the selectivity of aromatic separation from extract materials. The sulfur dioxide- BF_3 -sulfur compound secondary extract which is produced by the BF_3 contacting operation can be stripped to remove BF_3 and sulfur dioxide and a high sulfur concentrate can be withdrawn from the process.

It will also be apparent that the refining process of the present invention can be applied to a wide variety of aromatic and sulfur-containing materials, for example extracts obtained by known solvent extraction processes, for example processes for the selective extraction of hydrocarbon oils with organic solvents such as furfural, nitro-methane, dimethyl formamide, methanol and the like, or with inorganic solvents such as SbCl_3 , liquid hydrogen fluoride, etc.

It will be apparent from the discoveries underlying our refining process that the recovery of BF_3 from its mixtures with other gases, e. g., hydrocarbon gases, can be readily effected by selectively absorbing it in a liquid mixture of sulfur dioxide and a sulfur compound, e. g., a dialkyl sulfide, or in sulfur-containing sulfur dioxide extracts.

This is a continuation in part of our co-pending application, No. 182,613, filed August 31, 1950, now abandoned.

We claim:

1. A process for refining a hydrocarbon material, which process comprises contacting said hydrocarbon material with liquid sulfur dioxide in an amount in excess of its solubility in said hydrocarbon material under the conditions of said contacting and with BF_3 at a temperature between about 0° C. and about -85° C. under a pressure sufficient at least to maintain the liquid phase, and thereafter separating a refined hydrocarbon material and an extract solution in liquid sulfur dioxide and BF_3 .

2. A process for desulfurizing a sulfur-containing hydrocarbon material, which process comprises contacting said hydrocarbon material with liquid sulfur dioxide in an amount in excess of its solubility in said hydrocarbon material under the conditions of said contacting and with BF_3 in an amount between about 0.5 and about 5 mols per gram atom of sulfur contained in said hydrocarbon material at a temperature between about 0° C. and about -85° C. under a pressure sufficient at least to maintain the liquid phase, and thereafter separating a substantially desulfurized hydrocarbon material and an extract solution of

sulfur compounds in liquid sulfur dioxide and BF_3 .

3. A process for desulfurizing a sulfur-containing hydrocarbon material, which process comprises contacting said hydrocarbon material with between about 15 and about 200 percent by volume of liquid sulfur dioxide and with BF_3 in an amount between about 1 and about 3 mols per gram atom of sulfur contained in said hydrocarbon material at a temperature between about 0° C. and about -85° C. under a pressure sufficient at least to maintain the liquid phase, and thereafter separating a substantially desulfurized hydrocarbon material and an extract solution of sulfur compounds in liquid sulfur dioxide and BF_3 .
4. The process of claim 3 wherein about 2 mols of BF_3 are employed per gram atom of sulfur contained in said hydrocarbon material and the temperature is between about -10° C. and about -50° C.
5. The process of claim 3 wherein said hydrocarbon material is a naphtha.
6. The process of claim 4 wherein said hydrocarbon material is a kerosene.
7. The process of claim 4 wherein said hydrocarbon material is a heater oil.
8. The process of claim 4 wherein said hydrocarbon material is a furnace oil.
9. The process of claim 4 wherein said hydrocarbon material is a gas oil.
10. A process for the selective desulfurization of a hydrocarbon material containing both organic sulfur compounds and aromatic hydrocarbons which process comprises contacting said hydrocarbon material with between about 15 and about 200 percent by volume of liquid sulfur dioxide and with BF_3 in an amount between about 1 and about 3 mols per gram atom of sulfur contained in said hydrocarbon material at a temperature between about -10° C. and about -50° C. under a pressure sufficient at least to maintain the liquid phase, and thereafter separating a substantially desulfurized hydrocarbon material containing aromatic hydrocarbons and an extract solution of organic sulfur compounds and aromatic hydrocarbons in liquid sulfur dioxide and BF_3 , said extract solution being characterized by a ratio of organic sulfur compounds to aromatic hydrocarbons between about 1.5 and about 2.5.
11. A process for refining a hydrocarbon oil containing organic-sulfur compounds, which process comprises contacting said oil in the liquid phase, at a temperature below about +10° C., with liquid sulfur dioxide in an amount at least sufficient to form distinct extract and raffinate phases and in the presence of sufficient BF_3 to form complexes, and thereafter separating a raffinate phase containing a refined hydrocarbon oil from the extract phase containing said complexes.
12. The process of claim 11 which includes further steps of removing sufficient BF_3 and SO_2 from the extract phase to effect separation thereof into a second raffinate phase and a second extract phase which consists predominantly of organo-sulfur compounds, and separating said phases from each other.
13. The process of claim 12 wherein a portion of said second raffinate phase is recycled to said contacting step.
14. In the process of refining a hydrocarbon material containing organo-sulfur compounds and aromatic hydrocarbons by contacting said

15

hydrocarbon material with liquid SO₂ in an amount in excess of its solubility in said hydrocarbon material under the conditions of said contacting and with BF₃ in an amount between about 0.5 and about 5 mols per gram atom of sulfur contained in said hydrocarbon material at a temperature between about 0° C. and about -85° C. under a pressure sufficient at least to maintain the liquid phase and thereafter separating a raffinate phase consisting of a hydrocarbon material with a lower organo-sulfur compound content and an extract phase consisting of organo-sulfur compounds adducted with BF₃, SO₂, free BF₃ and aromatic hydrocarbons, the improvement wherein said extract phase is treated 10 to remove free BF₃ and SO₂ in order to obtain 15

16

5 a second raffinate phase consisting essentially of substantially all of said aromatic compounds and a minor amount of organo-sulfur compounds and a second extract phase consisting essentially of an organo-sulfur compound-BF₃ adduct and SO₂, and recycling said second raffinate phase to said contacting step.
